UNITED STATES PATENT OFFICE.

WILLIAM TWEEDDALE, OF BROOKLYN, NEW YORK.

WATER-CLOSET.

SPECIFICATION forming part of Letters Patent No. 279,048, dated June 5, 1883.

Application filed February 8, 1883. (No model.)

To all whom it may concern:

Be it known that I, WILLIAM TWEEDDALE, a subject of the Queen of Great Britain, residing at Brooklyn, in the county of Kings and State of New York, have invented new and useful Improvements in Water-Closets, of which the following is a specification.

This invention relates to novel means for securing the bowl of a water-closet and the valve-chamber to each other and to the siphon-trap; also, to a novel construction of the discharge-valve in the bowl and of the mechanism for controlling said valve, together with the flushing-valve.

15 The precise construction of the parts above named is pointed out in the following specification and illustrated in the accompanying drawings, in which—

Figure 1 represents a side view, partly in section. Fig. 2 is a longitudinal vertical section in the plane xx ; Fig. 3. Fig. 3 is a transverse vertical section in the plane yy ; Fig. 2. Fig. 4 is a detached elevation of the lifting-rod.

Similar letters indicate corresponding parts.

25 In the drawings, the letter A designates the bowl of a water-closet, which may be constructed of earthenware or of any other material suitable for the purpose, and which is provided with a discharge-valve, B, in one side, 30 near its bottom, while it connects at the opposite side, near its top, with the flushing-pipe C. O is the overflow-pipe. The valve B is secured to a rock-shaft, D, which has its bearings in the sides of the valve-chamber E, and 35 extends through one side thereof a sufficient distance to make room for a lever, F. The outer end of this lever extends through a slot, a , in the lifting-rod G, (see Fig. 4,) and is provided with a weight, b, which has a tendency 40 to keep the valve B closed.

The flushing-pipe C communicates with the water-supply pipe H by a valve, I, which may be termed the "flushing-valve," and which is situated in the valve-chamber J and closes up 45 against its seat c by the action of the weighted lever K. This lever has its fulcrum on a pivot, d, and it connects at one end with the stem e of the flushing-valve I, while its opposite end extends through a slot, f , in the lifting-rod, and 50 is provided with a weight, g. Between its pivot d and weight g the lever K is connected

to the air-cushioning piston L, which works in the cylinder M. In the bottom of this cylinder is a valve, h, which opens inward, and in the sides of said cylinder or in its bottom are 55 one or more small openings, i.

To the lower end of the lifting-rod G is secured a heavy weight, j. When the lifting-rod is raised by its handle k the discharge-valve B of the bowl and the flushing-valve I 60 are opened and the matter contained in the pan is washed out, while at the same time the air-cushioning piston L is raised up in the cylinder M. When the lifting-rod is permitted to drop the discharge-valve B is immediately 65 closed by the combined action of the weight b on the lever F and the weight j on the lifting-rod; but the flushing-valve I remains open for a short time after the discharge-valve has 70 closed, because the lever K is supported by the air-cushioning piston L, and the slot f in the lifting-rod is of such a length that the weight j of said lifting-rod does not bear upon the lever K. The air-cushioning piston is slowly 75 depressed by the weight g of the lever K, while the air from the lower portion of the cylinder M escapes through the opening or openings i. During this period of time the flushing-valve I remains open, and the required quantity of 80 water flows into the pan before said valve closes.

The valve-chamber E, which contains the discharge-valve B, is provided with a bottom flange, l, which is secured to the flange m of the siphon-trap P by screws n. In the interior of the valve-chamber is formed a recess, o, to receive a surrounding flange on the valve-seat Q, which is fastened by screws q passing through its flange. Between the inner surface of this flange and the breast of the pan is 85 formed a putty joint, r. The rear portion of the pan rests upon a cup-shaped support, S, which is fastened to ears s on the siphon-trap P, while the front portion of said bowl is provided with downwardly-projecting flange t, 90 which rests upon the flange l of the valve-chamber. On the siphon-trap P is formed a shoulder, u, and between this shoulder and the flange t is inserted a wedge, T, by preference of wood. By driving this wedge in, the breast 95 of the bowl is drawn up tight against the face of the valve-chamber, the putty joint r serv-

ing to prevent leakage. By these means the bowl can be very readily adjusted in position, and it can also be readily removed whenever it becomes desirable.

5 The discharge-valve B is constructed of two disks, *v* and *w*, the disk *v* being firmly mounted on the rock-shaft D, while the disk *w* is connected to the disk *v* by a screw, *a'*, passing through its center. On its inner surface said 10 disk *w* is provided with a rim, *b'*, and with an annular rib, *c'*, and inside of this annular rib is placed a gasket, *d'*, of elastic rubber or other equivalent material. By tightening up the screw *a'* the gasket *d'* is compressed to such 15 an extent that the disk *w* is firmly retained in position; but I do not screw up the screw *a'* sufficiently tight to cause the rim *b'* of the disk *w* to bear firmly all around against the inner surface of the disk *v*, so that in closing the 20 valve B the disk *w* can yield and accommodate itself to the valve-seat Q, the weight *j* on the lifting-rod and weight *b* on the lever F acting upon the valve B with sufficient pressure to produce the desired effect.

25 What I claim, and desire to secure by Letters Patent, is—

1. In a water-closet, the combination of the siphon-trap P, provided with the flange *m* and lateral ears *s*, the cup-shaped saddle S, detachably connected with the ears of the siphon-trap, the valve-chamber E, having a bottom flange, *l*, detachably connected with the flange of the trap, and the bowl A, joined at its breast end to the valve-chamber, and at its other end resting in the cup-shaped saddle, substantially as 35 described.

2. The combination of the siphon-trap P and valve-chamber E, detachably connected together, and the trap having a shoulder, *u*, with the bowl A, provided with a flange, *t*, a 40 putty joint, *r*, at the breast of the bowl, and a wedge, T, arranged between the shoulder on the trap and the flange on the bowl, substantially as and for the purpose described.

3. The combination, with the bowl A, valve-chamber E, and valve-seat Q, all detachably united, of the shaft D, extending through the valve-chamber, the valve B, hung on said shaft and composed of two disks and an interposed elastic gasket, the inner disk resting on the 45 valve-seat, the weighted lever F, attached to the shaft of the valve outside the valve-chamber, and the lifting-rod G, connected with the lever, substantially as described.

4. The combination, substantially as herein 50 described, of the pan A, the valve-chamber E, containing the discharge-valve B, the rock-shaft D, the lever F, extending through a slot in the lifting-rod G, the flushing-valve I, the air-cushioning piston L, and the lever K, connected to the flushing-valve and to the air-cushioning cylinder and extending through a 55 long slot in the lifting-rod and the flushing-pipe.

In testimony whereof I have hereunto set 60 my hand and seal in the presence of two subscribing witnesses.

WILLIAM TWEEDDALE. [L. S.]
